UNITED STATES PATENT OFFICE

JACOB HOFFMANN, OF HIGHLAND PARK, ILLINOIS, ASSIGNOR TO HUB METAL BED CO., OF CHICAGO, ILLINOIS, A CORPORATION OF ILLINOIS

DISAPPEARING BED

Application filed October 12, 1931. Serial No. 568,413.

This invention relates to new and useful improvements in disappearing beds and is particularly directed to the type of folding bed that is mounted within a shallow closet 5 or recess.

The objects of this invention are to provide a novel means for mounting such a folding bed within such a closet so that it may be swung out into the room in a variety of 10 positions to be unfolded for use and so that the plan dimensions of the containing closet need only be slightly larger than the plan of the folded bed.

Other objects are to provide supporting 15 means for the pivotally mounted end of the bed so that the strain is taken off the mounting means.

Other objects and advantages will be apparent from the following detailed description.

In the drawings:

Fig. 1 is a perspective view of a bed constructed in accordance with my invention swung partially out from the closet;

Fig. 2 is an enlarged detailed plan view of one of the pivot connections with the side of the closet;

Fig. 3 is a plan view of the bed in unfolded position in the room, the dotted lines indicating the successive stages of moving the folded bed from within the closet to the room.

Fig. 4 is a side elevation of the bed in unfolded position.

Fig. 5 is a side elevation showing the bed partially folded.

Referring more particularly to the drawings, 1 is the bed spring frame pivotally mounted at 2 in a vertical plane on supporting arms 3 which are secured to the vertical 40 arms of the head end frame by means of bolts 5. A vertically positioned rectangular supporting member 6 formed of bent tubing and having vertical and horizontal arms 6a and 6b, respectively, is pivotally mounted in a horizontal plane to the middle of the top and bottom arms of the head end frame 4 by means of horizontally extending bars 7 bolted to the top and bottom of the member 6 and bracket 8 and brace 9 secured to the top and bottom, respectively, of the head end

4. A closet 10 has a pair of doors 11 and mounted vertically on an outer edge of the closet is a metal anchoring angle bar 12 to which is hinged in a horizontal plane the member 6, as is shown in detail in Fig. 2. 55 Part of the hinges 12a are bolted to the extending part of the angle bar 12, the others 12b to one of the vertical arms 6a of member 6 and are pivotally joined together by pins 13.

In operation: The folded bed is positioned within the closet 10 and the doors 11 closed, thus hiding it from view. To unfold, the doors are opened and the unit is swung out of the closet by means of the hinged connections between member 6 and angle bar 12, as shown in dotted lines in Fig. 3. When it has been moved sufficiently far the bed itself is pivoted about the axis formed by the mountings between the head end 4 and the member 6, as again shown by dotted lines in Fig. 3. 65 It can be pivoted to numerous positions in the room and then the spring frame swung down to horizontal position, as shown in Figs. 4 and 5.

Feet 14 are provided for the foot end of the bed that swing open as the bed is lowered to horizontal position.

In the invention above described the entire weight of the head of the bed when in unfolded position and the entire weight of the whole bed when in folded position is borne by the member 6.

Another means for supporting the head end of the bed is a pair of feet 16, the ends of 85 which are pivoted to the side of the frame 1 at 17, the other ends being positioned within guides 18 secured to the supporting member 3. As the bed is lowered the feet come into supporting position, as shown in Fig. 4. 90

In the novel invention above described I provide a folding bed that may be completely concealed within a closet of comparatively small size and yet may be unfolded for use in a variety of positions in the room. 95

I claim:

1. A disappearing folding bed comprising a head end frame, a bed spring frame pivotally mounted thereon so as to be movable from vertical to horizontal position, a 100

rectangular supporting member of one piece continuous tubing comprising vertical and horizontal joined arms, horizontally extending bars fastened to said horizontal arms and 5 pivotally connected to substantially the middle of the top and bottom, respectively, of said head end frame adjacent the ends of one of said vertical arms, an anchoring member adapted to be secured in vertical position 10 within a recess in a room, the other of said vertical arms being hinged to said anchoring member.

2. A disappearing folding bed comprising a head end frame, a bed spring frame 15 pivotally mounted thereon so as to be movable from vertical to horizontal position, a rectangular supporting member of one piece continuous tubing comprising vertical and horizontal joined arms, horizontally extending bars fastened to said horizontal arms, brackets secured to substantially the middle of the top and bottom, respectively, of said head end frame, an anchoring member adapted to be secured within a recess in a 20 room, said horizontally extending bars being pivotally connected to said brackets and one of said vertical arms being hinged to said anchoring member.

3. A disappearing folding bed comprising 30 a head end frame, a bed spring frame pivotally mounted thereon so as to be movable from vertical to horizontal position, a rectangular supporting member of one piece continuous tubing comprising vertical and horizontal 35 joined arms, horizontally extending bars fastened to said horizontal arms, brackets secured to substantially the middle of the top and bottom, respectively, of said head end frame, an anchoring member comprising an 40 angle bar adapted to be secured within a recess in a room, hinge members fastened to said anchoring member, hinge members fastened to one of the vertical arms of said supporting member, said horizontally extending 45 bars being pivotally connected to said brackets and said hinge members pivotally joined together.

4. A disappearing folding bed comprising a head end frame, a bed spring frame 50 pivotally mounted thereon so as to be movable from vertical to horizontal position, a rectangular supporting member of one piece continuous metal comprising vertical and horizontal joined arms, horizontally extending 55 bars rigidly fastened to said horizontal arms and parallel thereto and pivotally connected to substantially the middle of the top and bottom, respectively, of said head end frame adjacent the ends of one of said vertical arms, an anchoring member adapted to be 60 secured within a recess in a room, the other of said vertical arms being hinged to said anchoring member.

JACOB HOFFMANN.
